UNITED STATES PATENT OFFICE.

HENRY J. CARROLL, OF PROVIDENCE, RHODE ISLAND, ASSIGNOR TO H. LEDERER & BRO. INC., OF PROVIDENCE, RHODE ISLAND, A CORPORATION OF RHODE ISLAND.

DESIGN FOR A FOB, PENDANT, BROOCH, PIN, OR SIMILAR ARTICLE.

51,954.

Specification for Design.

Patented Apr. 9, 1918.

Application filed February 2, 1918. Serial No. 215,208. Term of patent 3½ years.

To all whom it may concern:

Be it known that I, HENRY J. CARROLL, a citizen of the United States, residing at the city and county of Providence, State of Rhode Island, have invented a new, original, and ornamental Design for a Fob, Pendant, Brooch, Pin, or Similar Article, of which the following is a specification, reference being had to the accompanying drawing, forming part thereof.

The figure is a face view of a fob, pendant, brooch, pin or similar article, illustrating my new design.

I claim:

The ornamental design for a fob, pendant, brooch, pin, or similar article, as shown.

HENRY J. CARROLL.

Witnesses:

HOWARD E. BARLOW,
J. L. MACDERMOTT.
